INVENTOR

George M. Atall.

UNITED STATES PATENT OFFICE.

GEORGE M. ATALL, OF IONA, SOUTH DAKOTA, ASSIGNOR OF ONE-HALF
TO WILLIAM J. FAY, OF FOREST GLEN, MARYLAND.

CHECKREIN-HOLDER.

SPECIFICATION forming part of Letters Patent No. 783,008, dated February 21, 1905.

Application filed June 6, 1903. Serial No. 160,321.

To all whom it may concern:

Be it known that I, GEORGE M. ATALL, a citizen of the United States, residing at Iona, in the county of Lyman and State of South Dakota, have invented a new and useful Improvement in Checkrein-Holders, of which the following is a specification.

My invention relates to a new and useful improvement in checkrein-holders; and the object of my invention is to provide a simple, inexpensive, and efficient one adapted to be readily applied to the saddle of the harness or the like, similar to an ordinary checkrein-hook, and capable of enabling a checkrein to be readily attached to and detached from the saddle or the like, wherein there is no danger of their accidental or undesigned disengagement by the movements of the animal's head.

With these and other objects in view my invention consists in certain features of constructions hereinafter specified, and particularly pointed out in the claims hereto appended.

In the accompanying drawings, Figure 1 is a side view of my improved checkrein-hook, showing an overdraw - checkrein attached thereto. Fig. 2 is a perspective view in detail of a part which attaches to an overdraw-checkrein, while Fig. 3 is a top plan view of a slightly different construction of a checkrein-loop, showing a side checkrein attached thereto. Fig. 4 is a top plan view in detail, showing modified means for attaching the hook to the saddle of a harness. Fig. 5 is a top view of the bearing-plate as shown in Fig. 3 by the dotted lines. Fig. 6 is a longitudinal sectional view of my complete device, and Fig. 7 is a perspective view of the bearing-plate 13.

Similar numerals of reference designate corresponding parts in the accompanying drawings.

Referring to the accompanying drawings, 1 indicates a checkrein of the usual form.

2 indicates a leather tongue or other flexible material, having at one end an aperture 3, de-

signed to admit a checkrein and having a buttonhole consisting of a slit 4, terminating at one end in a circular hole 5, adapted to engage the hook or button 6.

6 indicates a hook or button formed of an oblong-shaped head 7, forwardly projecting, a neck 8, around which the circular hole 5 is seated between the head 7 and the base 9, and having a base-plate adapted to be secured to a stationary support provided with eyes 10 for fastening purposes, as shown in Figs. 4 and 6, and the loop 11 is to engage a crupper-strap, or said holder 6 may be supported by the usual threaded shank 12, as shown in Fig. 1. While these are the preferred means for attaching the device, other known means may be employed without departing from the spirit of my invention.

In carrying out my present invention I have provided a bearing-plate consisting of a metallic plate 13, as best shown in Figs. 5 and 7 of the drawings. The intermediate portion of the plate 13 is stamped out, forming the fastening fingers or points 14, which are passed through the strap 2 and bent down against the outside of the strap, thereby securely fastening the bearing-plate 13 in the aperture 3, the edges of the metallic plate being concaved at the ends 15 and convexed on the sides 16. This arrangement being applied strengthens and stiffens the loop and permits the checkrein to move freely with the movement of the animal's head.

The buttonhole in the tongue 2 is so shaped to engage the holder 6 when turned in a manner admitting the forward projecting part of the hook or button first, thus making it safe from undesigned disengagement and constituting a durable and an effective device.

What I claim as my invention, and desire to secure by Letters Patent, is—

1. In a checkrein-holder the combination with a device comprising a neck, having a forwardly-projecting head thereon, and a base-plate extending laterally beyond the head to the front and rear thereof, of a flexible hook-

strap having a slit therein, and a circular aperture joining the slit, at the rear end of the latter, substantially as described.

2. A checkrein-holder consisting of a device comprising a base, a neck, having a forwardly-projecting head lying parallel with said base, a hook-strap doubled upon itself to form an aperture to receive a checkrein, and a rectangular bearing-plate applied within the aperture of said hook-strap, and having retaining-points struck up from the intermediate portion of said bearing-plate passed through said strap and bent downwardly against the outside of the same, substantially as described.

15 3. In a checkrein-holder consisting of a hook-strap, having at one end an aperture adapted to receive a side checkrein, and a bearing-plate 13, applied in said aperture, said bearing-plate having upwardly-turned curvilinear flanges formed upon its ends, and downwardly-turned curvilinear flanges formed upon

its sides, and the intermediate portion stamped out forming fastening-fingers, substantially as and for the purpose described.

4. In a checkrein-holder, a flexible strap 25 doubled and secured to itself, and a reinforcing rectangular bearing-plate 13, provided with fastening fingers or points 14, struck up from the intermediate portion of said bearing-plate, passed through said strap and bent downwardly against the outside of the same, thereby 30 securely fastening said bearing-plate in the aperture of said hook-strap, for the purpose described.

In testimony whereof I have signed my name 35 to this specification in the presence of two subscribing witnesses.

GEORGE M. ATALL.
